(57) **CLAIM**

The ornamental design for a dispenser for toilet cleansing, as shown and described.

DESCRIPTION

FIG. 1 is a top, front, right side, perspective view of a first embodiment of a dispenser for toilet cleansing showing my new design;

FIG. 2 is a top, rear, left side, perspective view thereof;

FIG. 3 is a front view thereof;

FIG. 4 is a rear view thereof;

FIG. 5 is a right side view thereof, the opposite side being a mirror image;

FIG. 6 is a top view thereof;

FIG. 7 is a top, right side, front, perspective view of a third embodiment thereof;

FIG. 8 is a top, left side, rear, perspective view thereof;

FIG. 9 is a front view thereof;

FIG. 10 is a rear view thereof;

FIG. 11 is a right side view thereof, the opposite side being a mirror image; and,

FIG. 12 is a top view thereof.

The environmental material shown in broken lines forms no part of the design.
